2 Sheets-Sheet 1

A technical line drawing of a rectangular electrical device, possibly a power supply or generator. The front panel features two vertical handles (1) on the left. On the left side, there are two groups of three circular terminals (28, 29, 30) and two rectangular terminals (23, 24). On the right side, there are two vertical slots (7) and a small rectangular terminal (26). The top panel has a handle (4) and a small rectangular terminal (54). The right side panel has a vertical slot (5) and a handle (3). The back panel is labeled with the letter 'B'.

Fig. 3.

A technical line drawing of a rectangular metal frame with a hatched pattern. Inside, there are vertical bars labeled 16 and a central slot labeled 8. A curved piece labeled 19 is positioned above the slot. A strap labeled 18 with a buckle is attached to the right side. A small number '1' is near the top center, and a small number '7' is near the bottom left corner.

UNITED STATES PATENT OFFICE

2,390,922

PROJECTOR UTILITY CASE

Arnold Bert Coleman, Chicago, Ill.

Application December 7, 1943, Serial No. 513,282

1 Claim. (Cl. 177—311)

This invention relates to new and useful improvements in a case which employs certain characteristics especially adapted for use by operators of motion picture projectors, the principal object being to provide a case which employs certain electrical switching means, whereby current can be supplied to the projector and also to floor lamps, all being controlled conveniently by the operator of the projection machine.

Another object of the invention is to provide a compact apparatus for not only housing reels of film, the projection machine and other miscellaneous items, but wherein electrical requirements are satisfied to a highly efficient and readily accessible extent.

Another important object of the invention is to provide a case of the character stated which can serve as a stand for a projector, when projecting motion pictures.

Other objects and advantages of the invention will become apparent to the reader of the following description.

In the drawings:

Figure 1 is a perspective view of the apparatus.

Figure 2 is a fragmentary front elevational view with the door in open position.

Figure 3 is a horizontal sectional view on line 3—3 of Figure 1.

Figure 4 is a fragmentary enlarged detailed sectional view taken on the line 4—4 of Figure 1.

Figure 5 is a fragmentary enlarged detailed sectional view taken on the line 5—5 of Figure 1.

Figure 6 is a plan view of a dual plug cord such as is used in conjunction with the present invention.

Figure 7 is a diagrammatic view showing the electrical connections between the electrical elements employed.

Referring to the drawings, wherein like numerals designate like parts, it can be seen that numeral 5 generally refers to the case and this consists of a boxed portion A and a door B. The door B is hinged, as at 6, to the box A and suitable fastening means 7 is provided for securing the door to the box in closed position.

In the box portion A is a vertical partition 8 adjacent one wall of the box and the space between the partition and the adjacent box wall is divided by horizontal partitions 9, 10 and by a vertical partition 11 between the bottom of the box A and the horizontal partition 10. Thus, this space is divided into compartments 12, 13, 14 and 15. The compartment 12 preferably has certain dividers 16 therein for holding film reels. The compartment 13 is for miscellaneous items.

The compartment 15 may be used for electrical cords and the compartment 14 is closed in to house an electrical receptacle.

In the remaining space of the box A, that is, the compartment 17, are straps 18, 19 provided with a buckle 20 for holding a movie projector firmly in position.

Set in the top portion of the box A is a tell-tale lamp 21 having sufficient candlepower to afford sufficient light through an adjacent windowed port 22 so that the operator may read indicia on the reel and have illumination for other purposes. The tell-tale lamp 21 therefore serves the dual purpose of indicating when the electrical features of the apparatus are in use and also affording illumination.

A pocket 23 is provided in the upper portion of one side wall of the box A, and in the back of this pocket are located three switches (preferably of the toggle type) which are denoted by numerals 24, 25 and 26. At this point, it will be observed that the top of the box A is preferably of double wall construction with the two walls spaced apart to accommodate not only the lamp 21, but also the switches 24, 25 and 26.

Located on a panel set flush in the lower portion of the same side wall of the box A is a single electrical receptacle 28, a double electrical receptacle 29 and another single electrical receptacle 30.

As can be seen in Figure 7, the switch 26 has one side connected to the tell-tale lamp 21, while the other side of the tell-tale lamp 21 is connected by the conductor 22 to one side of each of the receptacles 28, 29 and 30. A conductor 32 extends to one side of each of the switches 24, 25 and 26, the remaining sides of the switches 24 and 25 being connected by conductors 33 and 34 to the remaining sides of the receptacles 29 and 30.

It can now be seen that with a cord 35 having a plug 36 at each end thereof, one end of the cord can be connected with a supply receptacle, while the other is plugged into the receptacle 28.

Floor lamps (not shown) can be connected to the double receptacle 29 and controlled by the switch 24. The movie projector (not shown) can be plugged into the receptacle 30 and controlled by the switch 25.

As before stated, the tell-tale lamp 21 serves the dual purpose of furnishing some illumination for use by the operator and also as an indicator that the electrical apparatus is in operation.

While the foregoing specification sets forth the invention in specific terms, it is to be under-

stood that numerous changes in the shape, size and materials may be resorted to without departing from the spirit and scope of the invention as claimed hereinafter.

Having described the invention, what is claimed as new is:

In apparatus of the class described, a box having sides and a double-walled top forming an upper space in the box opening onto one side of said box, electrical plug-in receptacles set into 10 said side of the box adjacent to the bottom thereof including an input receptacle and a plu-

rality of output receptacles, switches set into said space at said side of the box, and a tell-tale light in said space in the center of the top visible through the top of the box, one of said switches and the tell-tale light being connected in circuit with the input receptacle, the plurality of output receptacles being each connected across the input receptacle, the other switches being each connected in series with one of the output receptacles.

ARNOLD BERT COLEMAN.
